UNITED STATES PATENT OFFICE

2,548,745

ELECTROLYTIC RHEOSTAT

Victor H. Smith, Phoenix, Ariz.

Application May 18, 1950, Serial No. 162,714

9 Claims. (Cl. 201—57)

1

This invention pertains to improvements in electrical control mechanisms, and is particularly directed to improvements in electrolytic rheostats.

One of the objects of this invention is to provide a rheostat control mechanism of high sensitivity and accuracy of control over a wide range of speeds for a motor to be controlled by the mechanism.

Still another object of this invention is to provide an improved electrolytic rheostat capable of sensitive and fine adjustments for regulating the speed of an operating motor controlled by the rheostat.

Another object of this invention is to provide a speed variation control rheostat for a motor utilizing an electrolyte and adjusting a pair of electrodes in the electrolyte to effect a speed variation control for an electric motor connected to said rheostat.

Another object of this invention is to provide an improved electrolytic rheostat for an alternating current sewing machine motor.

It is also an object of this invention to provide an improved electrolytic rheostat in which the electrolyte is contained in a completely enclosed chamber and in which one of the electrodes is movable relative to the other electrode from a position removed from the electrolyte, through the electrolyte, to a position of direct contact with the other electrode.

Further features and advantages of this invention will appear from a detailed description of the drawings in which:

Figure 1 is a plan view of an electrolytic rheostat incorporating the features of this invention.

Figure 2 is a vertical transverse section through the rheostat indicated by the line 2—2 in Figure 1.

Figure 3 is an enlarged fragmentary sectional view on the line 3—3 of Figure 1.

As exemplary of one embodiment of this invention there is shown a structure comprising a tank 10 composed of suitable insulative material which may be of any well known plastic substance such as Bakelite, or the like in which is contained a dilute solution 11 of sodium chloride or calcium chloride to form an electric conducting solution of relatively high resistance. The solution is maintained at a level 12 in the tank 10. The tank is totally enclosed by means of a cover 13 also of suitable insulative material in which is carried one fixed electrode 14 held in place by suitable nuts and washers 15. One

2

power supply line L1 is connected to the electrode 14 by a suitable binding post 16.

Movably mounted in the tank 10 is the second electrode 17 which is supported on a rocking yolk piece 18 having trunnions 19 journaled in suitable bearings 20 formed in the cover member 13 and opening into a bore 21 also formed in the cover member 13. Directly above the rocking yolk piece 18, as best seen in Figure 3, is a flexible diaphragm 22 of suitable insulative material 22 which is secured to the top surface 23 of the cover member 13 by the clamp plate 24 and appropriate screws 25 so as to form a liquid tight seal between the surface 23 and the flexible diaphragm 22. The clamp plate 24 is provided with a bore 26 of similar size to the bore 21 in the cover member 13.

The electrode 17 projects upwardly through the yolk member 18 through the diaphragm 22 and is rigidly locked together with both of these members by means of suitable washers and nuts 27. The electrode 17 therefore rocks about the axis of the trunnions 19 while at the same time the chamber 28 within the tank 10 is sealed off through the flexible diaphragm 22 for any position of movement of the electrode 17. The other power supply line L2 is suitably connected to the electrode 17 by means of a suitable binding post 29 mounted on the outer end of the movable electrode 17.

The electrode 17 is so constructed and bent at 30 that it normally lies in a horizontal position 17a completely removed from the electrolyte 11 in the tank member 10 and it may swing to intermediate position such as position 17b or to fully open position of no resistance of current flow from L1 to L2 such as at 17c. In position 17c the electrode 17 may directly contact the electrode 14 at the point 31 with both electrodes 40 fully submerged in the electrolyte 11.

Normally, the electrode 17 is held in the biased disconnect position 17a by means of the tension spring 32 which is connected to the electrode 17 by means of the piece 33 secured to it by a suitable nut 34 below the binding post 29, the other end of the spring being connected by a suitable link or hook piece 35 rigidly secured to the tank 10. The piece 33 is connected through suitable links 36 and 37 interconnected by means of an insulative link 38 to the lever arm 39 of the knee actuating lever 40 pivotally mounted on a suitable pin 41 carried in a suitable manner, as by a bracket 42 on the tank member 10. A stop pin 43 located in rigid position relative to the tank member 10 engages the edge 44 of the lever arm

39 so as to limit the normal stop position by the spring 32 of the electrode 17 to the position 17a shown in Figure 2. A curved knee engaging portion 40a may be provided on the lever 40 for ready operation of the rheostat by the operator of a sewing machine or any other machine being driven by a motor energized through the rheostat.

The solution 11 in the tank member 10 is normally hermetically sealed off in the tank 10 by means of a suitable rubber cork or closure cap 45 which may contain a microscopic vent hole 46 to allow for contraction and expansion of the liquid 11 and gas pressure or air in the chamber 28. The opening 46 may be of such small size however that the liquid 11 cannot escape therethrough though the gas in the chamber 28 may be readily vented through the cork 45.

With the lines L1 and L2 connected in series with one power supply line of a source of power and with one terminal of an electric motor or other device to be controlled, the switch may be operated from a no current flow position of the control lever 40 as shown at 40a with the electrode 17 in the position 17a to engage the electrode 17 with the solution 11 in varying degrees. At various intermediate positions 17b the motor or device may be energized more or less to effect its speed of operation with an extreme nicety and precision of speed regulation being obtained. Finally as greater and greater speeds are desired as in moving the control lever from position 40b down to position 40c, the electrode 17 is finally brought into direct contact with the electrode 14 at the point 31 to give full voltage nonresistance connection through the rheostat from lines L1 to L2 for maximum power and full speed operation of the machine being controlled. It is to be further noted that in this arrangement the initial stages of contact between position 17a and 17b of the electrode 17 with the surface 12 of the solution 11 takes place at a greater rate and sensitivity than relative movement from position 17b to 17c. This results in excellent low speed range control for the device connected to be controlled by this improved electrolytic rheostat.

Having thus fully described this invention and its numerous attendant advantages, it is obvious that many changes may be made in the form, construction and arrangement of the parts without departing from the spirit or scope of the invention or sacrificing its attendant advantages, the form herein described being a preferred embodiment for purposes of exemplifying this invention.

What is claimed is:

1. An electrolytic rheostat comprising a tank, a cover fixed on said tank, an electrolyte in said tank, a fixed electrode supported from said cover in said tank submerged in said electrolyte, a movable electrode, means for mounting said movable electrode on said cover, and means for actuating said movable electrode from a position above the electrolyte in said tank to intermediate positions of partial submergence in said electrolyte.

2. An electrolytic rheostat comprising a tank, an electrolyte in said tank, a fixed electrode in said tank submerged in said electrolyte, a movable electrode, means for mounting said movable electrode on said tank, and means for actuating said movable electrode from a position above the electrolyte in said tank to intermediate positions of partial submergence in said electrolyte, and

finally to a position of maximum submergence and direct contact with said fixed electrode.

3. In an electrolytic control rheostat having a tank containing a fluid electrolyte, a fixed electrode submerged in said electrolyte and rigidly mounted on said tank, a movable electrode, means for movably mounting said movable electrode on said tank, yielding means for normally holding said movable electrode in a disconnected position out of said electrolyte, and an operating lever connected to said movable electrode to move it into and through said electrolyte.

4. In an electrolytic control rheostat having a tank containing a fluid electrolyte, a fixed electrode submerged in said electrolyte and rigidly mounted on said tank, a movable electrode, means for movably mounting said movable electrode on said tank, yielding means for normally holding said movable electrode in a disconnected position out of said electrolyte, and an operating lever connected to said movable electrode to move it into and through said electrolyte to a position of engagement with said fixed electrode.

5. In an electrolytic rheostat having a tank containing fluid electrolyte, a fixed electrode submerged in said electrolyte, a movable electrode, means for movably mounting said movable electrode on said tank comprising a trunnion member pivotally journaled on said tank, a flexible diaphragm secured to said tank, and means securing said movable electrode, trunnion member, and said diaphragm rigidly together to provide support for said movable electrode on said tank.

6. In an electrolytic rheostat having a tank containing fluid electrolyte, a fixed electrode submerged in said electrolyte, a movable electrode, means for movably mounting said movable electrode on said tank comprising a trunnion member pivotally journaled on said tank, a flexible diaphragm secured to said tank, and means securing said movable electrode, trunnion member, and said diaphragm rigidly together to provide support for said movable electrode on said tank, bias spring means connected to said movable electrode to normally yieldingly hold said movable electrode in a disconnected position out of said electrolyte, and an actuating lever pivotally mounted relative to said tank and connected by linkage means to said movable electrode for moving said movable electrode into and through said electrolyte and into engagement with said fixed electrode.

7. In an electrolytic rheostat having a tank, an electrolyte in said tank, electrodes in said tank movable relative to each other in said electrolyte, and means for sealing said tank comprising a resilient plastic cork or the like having a microscopic vent therein secured in an access opening of said tank.

8. In an electrolytic rheostat structure having a tank, an electrolyte in said tank, a fixed electrode having a horizontal member located in said electrolyte near the bottom of said tank, a movable electrode pivotally mounted at the top of said tank having a member normally held in horizontal position at the top of said tank and above said electrolyte, and means for pivotally actuating said movable electrode to swing its outer end downwardly through said electrolyte relative to the horizontal member of said fixed electrode.

9. In an electrolytic rheostat structure having a tank, an electrolyte in said tank, a fixed electrode having a horizontal member located in said electrolyte near the bottom of said tank, a mov-

able electrode pivotally mounted at the top of said tank having a member normally held in horizontal position at the top of said tank and above said electrolyte, and means for pivotally actuating said movable electrode to swing its outer end downwardly through said electrolyte relative to the horizontal member of said fixed electrode and finally into direct contact with said horizontal member of said fixed electrode.
